PROCESS OF MAKING RECORD

David C. Rockola, Chicago, Ill., assignor to Rock-Ola Manufacturing Corporation, Chicago, Ill., a corporation of Delaware

Application March 12, 1941, Serial No. 382,951

4 Claims. (Cl. 117—113)

This invention relates to the structure of records for the recording and reproduction of sound and to a process for making such records.

An object of this invention is to provide a record structure having a margin of increased thickness which serves as a guide or indicator to show the proper starting position in the use of the record structure.

Another object of this invention is to provide a record having a margin of a color contrasting with that of the recording material, which margin not only serves as a guide or indicator of the starting position, but also provides a distinctive indication of the type or grade of the record.

Another object of this invention is to provide a process for making record blanks having a margin of increased thickness and a distinctive color.

Other objects of this invention relate to various features of construction and arrangement of parts which will be apparent from a consideration of the following specification and accompanying drawings, wherein

Figures 1, 2 and 3 are side elevational views of apparatus utilized in a preferred process of making record blanks in accordance with this invention, in which views parts of the apparatus are shown in section.

Figure 4 is plan view of a preferred form of record blank made in accordance with the present invention.

Figure 5 is an enlarged fragmentary sectional view taken substantially on line 5—5 of Figure 4 and looking in the direction indicated by the arrows.

Having particular reference to the drawings, a plurality of record matrices 10, which may be made of cardboard, fiber or sheet metal, such as aluminum or steel, are preferably concentrically mounted on a shaft 12 and separated by spacers, such as 13. The matrices 10 have central openings, such as that indicated at 14 in Figure 4, through which the shaft 12 extends. The group of matrices is held in position on the shaft between nuts 15 and 16, which are threaded onto the shaft. The ends of the shaft are provided with bearings 17 and 18, which fit into and are rotatably supported by the bearing slots 19 and 20 respectively on end walls 22 and 23 of a tank or vat 24. The rotatably supported and manually operable bearing covers 25 and 26 are preferably provided for the bearing slots 19 and 20 respectively to hold the shaft in place.

The tank or vat 24 is preferably supported from a foundation, which is indicated at 27, through feet, such as 28 and 29; the feet being secured

to the tank by bolts, such as 30, or other suitable fastening means, and to the foundation by bolts such as 32, or other suitable fastening means. The tank 24 is kept filled to a predetermined level through a connecting pipe 33 with one of the well-known record coating lacquers or record coating compounds; said level being indicated at 34, which is preferably slightly below the outer surfaces of the spacers 13.

10 The matrices, when mounted on the shaft 12 as shown, dip edgewise into the record coating compound or lacquer when the shaft is placed in the bearings 19 and 20 and are preferably substantially perpendicular to the surface of the compound or lacquer. A crank 35 is drivingly connected to one end of the shaft 12 to effect rotation of the shaft and the matrices whereupon all but the central portions of the matrices are coated with a smooth layer of the compound or lacquer.

20 After coating the matrices as described, they are preferably placed in a drying oven 36 for drying and baking to dry and solidify the record compound or lacquer. This is preferably effected 25 without removing the matrices 10 which have been coated from the shaft 12. The oven preferably has tracks 37 and 38 supported therein as by securing to the side walls 39 and 40 respectively, which tracks support chains 42 and 43, which have rollers such as 44 and 45 thereon and notched supports 46 and 47 for holding the ends of the shaft 12. The chains act as conveyors to carry series of coated matrices through the oven. The oven burners are indicated at 30 48 and 49.

35 After being dried or baked, the coated matrices are again replaced in the vat or tank 24 to the same depth for applying a second coat of the lacquer or compound. After each coating of compound or lacquer the coated matrices are again baked in the oven 36. This alternate coating and baking of the matrices is carried on until the coating is of a sufficient depth to receive the desired sound recording track. Usually three coats of the lacquer or compound is sufficient.

40 After the recording surface has been provided by coating the matrices 10 as described, the record blanks thus formed are preferably placed, in accordance with the instant invention, in a tank or vat 50, the construction of which tank or vat is similar to that described with respect to the tank or vat 24 and on which similar numerals refer to similar parts. This tank 50 has a lower level of compound or lacquer therein, which is indicated at 52; this level being such that only

the edges and margins of the record blanks dip into the compound or lacquer. Upon rotation of the crank 35 the edges and the margins of the record blanks are coated with an additional layer of compound of lacquer, which is preferably of a different color than that used in coating the recording surface of the blanks.

Referring particularly to Figures 4 and 5, the record blanks made by the process described herein have the matrix 10 coated on both sides as indicated at 53 and 54 with a coating of record compound or lacquer of sufficient depth to receive a sound recording track. The edge 55 and margins 56 and 57 on both sides of the record blank have an additional coating, which is preferably of a different color from the previously applied compound. This provides a margin of increased thickness at the edge of the record; the width of which margin is preferably such that it indicates the proper starting position for making a recording on the record blank. When the marginal coating is a distinctive color as preferred, this starting position is easily distinguished on the surface of the record. Also where different matrix materials are utilized for records of different quality and also where different record coating compounds or lacquer are used on different qualities of records, the particular distinctive colors utilized are preferably chosen to indicate the types of record blanks. The uncoated space 58 at the center or middle portion of the record is left for the application of a title sticker or other identifying indicia. On some forms of blanks it is preferable to have an opening such as 59 off-set from the central opening 14.

While the preferred embodiment of the invention has been shown and described, it will be apparent that various changes in details may be resorted to without departing from the spirit of the invention as defined by the appended claims.

I claim:

1. The process of making record blanks for the recording and reproduction of sound which comprises the steps of mounting a plurality of record matrices concentrically and in spaced relation upon a shaft, dipping the matrices edgewise a plurality of times to a predetermined depth into a record coating lacquer and rotating the matrices each time they are dipped thereby to coat all but the central portions of the matrices with said lacquer, baking the mounted and dipped matrices

after each dipping in the lacquer, dipping the coated matrices edgewise in a coating liquid to a depth less than said predetermined depth and rotating the coated matrices to form a rim of a coating liquid thereon, again baking the coated matrices, and removing the coated matrices from said shaft.

2. The process of making record blanks for the recording and reproduction of sound which comprises the steps of dipping a record matrix edgewise into a record coating lacquer to a predetermined depth and rotating the matrix about its center while dipped to said predetermined depth, baking the dipped matrix, dipping the coated matrices edgewise in a coating liquid to a depth less than said predetermined depth and rotating the coated matrices to form a rim of the coating liquid thereon, again baking the coated matrices, repeating the steps of dipping to a predetermined depth, rotating and baking until a coating of baked record coating lacquer of predetermined thickness is accumulated on the matrix, dipping less than said predetermined depth and rotating the coated matrix to form a rim of the coating liquid thereon, and again baking the coated matrix.

3. The process of making record blanks for the recording and reproduction of sound which comprises the steps of mounting a plurality of record matrices concentrically and in spaced relation upon a shaft, dipping the matrices edgewise a plurality of times to a predetermined depth into a record coating lacquer and rotating the matrices each time they are dipped thereby to coat all but the central portions of the matrices with the lacquer, baking the mounted and dipped matrices after each dipping in the lacquer, and removing the coated matrices from said shaft.

4. The process of making record blanks for the recording and reproduction of sound which comprises the steps of dipping a record matrix edgewise into record coating lacquer to a predetermined depth and rotating the matrix about its center while dipped to said predetermined depth, baking the dipped matrix and repeating the steps of dipping to a predetermined depth, rotating and baking until a coating of baked lacquer of predetermined thickness is accumulated on the matrix.

DAVID C. ROCKOLA.
